(57) **CLAIM**

We claim the ornamental design for an reader device for an analyte detection system, as shown and described.

DESCRIPTION

FIG. 1A is a top, front, and left side perspective view of a reader device, which forms a portion of an analyte detection system;

FIG. 1B is a left side view thereof;

FIG. 1C is a right side view thereof;

FIG. 1D is a top view thereof;

FIG. 1E is a bottom view thereof;

FIG. 1F is a front view thereof; and,

FIG. 1G is a rear view thereof.

The ornamental design which is claimed is shown in solid lines in the drawings. The broken lines formed by dashes show unclaimed subject matter and form no part of the claimed design. The dash-dot-dash lines in the drawings represent boundaries of claimed subject matter and form no part of the claimed design.
